(57) **CLAIM**

The ornamental design for a dome shaped structure for use as a planter, as shown and described.

DESCRIPTION

FIG. 1 is a perspective view illustrating my ornamental design for a dome shaped structure;

FIG. 2 is a top view of the dome shaped structure shown in FIG. 1;

FIG. 3 is a bottom view of the dome shaped structure shown in FIG. 1; and,

FIG. 4 is a side view of a representative side of the dome shaped structure shown in FIG. 1.

1 Claim, 4 Drawing Sheets

FIG. 2

FIG. 3
